(57) **CLAIM**

The ornamental design for a smart phone stand with communication and lamp function, as shown and described.

DESCRIPTION

FIG. 1 is a front perspective view of a smart phone stand with communication and lamp function showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view showing the design in use.

The broken lines in the drawings depict environment and are for the purpose of illustrating unclaimed portions of the smart phone stand with communication and lamp function and form no part of the claimed design.

1 Claim, 6 Drawing Sheets
